AIR STOPPER AND HOLDER FOR TOY
BALLOONS

George Magran, New York, N. Y.

Application August 24, 1939, Serial No. 291,677

5 Claims. (Cl. 46—90)

This invention relates to new and useful improvements in an air stopper and holder for toy balloons.

The invention has for an object the use of a spherical member, in conjunction with a toy balloon having a neck portion through which it may be inflated, arranged so as to be normally disposed within the balloon and adapted to plug said neck portion, and an element attached to 5 said spherical member and extending from said neck portion by which the spherical member may be moved into plugging condition.

Still further the invention proposes to so arrange the element mentioned in the previous 15 paragraph that it may also be used as a holder for the inflated toy balloon.

A further object of this invention resides in constructing the spherical member of certain kinds of material adapted to accomplish the 20 plugging operation in an efficient manner.

Still further the invention proposes a novel method by which the spherical member may be disposed within the balloon.

The dominating feature of the construction resides in the fact that the balloon may be inflated by blowing into the neck portion, and after it has been inflated as desired, the element 25 may be pulled to cause the spherical member to assume a position in the neck portion of the balloon to plug the same. Thus the balloon will 30 maintain its inflated condition.

A further object of the invention resides in a modified arrangement by which the spherical member may be slightly expanded, when desired, after it has been disposed within the neck portion 35 of the balloon to further assist in the plugging operation previously mentioned.

Still further the invention proposes the construction of a stopper and holder for toy balloons as mentioned which is simple and durable and 40 which may be manufactured and sold at a reasonable cost.

For further comprehension of the invention, and of the objects and advantages thereof, reference will be had to the following description 45 and accompanying drawing, and to the appended claims in which the various novel features of the invention are more particularly set forth.

In the accompanying drawing forming a material part of this disclosure—

50 Fig. 1 is a side elevational view of a toy balloon with an air stopper and holder associated therewith, in accordance with this invention.

Fig. 2 is a fragmentary perspective view of 55 the spherical member and holding element, per se.

Fig. 3 is a fragmentary sectional view taken on the line 3—3 of Fig. 1.

Fig. 4 is a fragmentary schematic view of the balloon and the spherical member as they appear

during one step of the process for associating these parts with each other.

Fig. 5 is a sectional view of a spherical member and holding element constructed according to a modified form of this invention.

Fig. 6 is a sectional view similar to Fig. 3 but illustrating the spherical member shown in Fig. 5, in use.

The air stopper and holder for toy balloons in accordance with this invention is used in combination on a conventional toy balloon 10 having a neck portion 11 through which it may be inflated. The air stopper and holder includes a spherical member 12 normally disposed within the balloon free from the neck portion 11, and 15 adapted to be moved into the base part of the neck portion for plugging the same. An element 14 is attached to the spherical member 12 and extends up through the neck portion 11 by which the spherical member 12 may be manipulated 20 as desired.

Preferably the spherical member 12 is made from rubber, though other materials may be used with some satisfaction, as for example cork. The element 14 may comprise a cord or an elastic band. At its extended end it is provided with a ring 15, or other member, by which it may be gripped. If the element 14 is elastic it may be knotted upon the ring 15 by slipping one end of the band through the ring, and then passing the 25 other end of the band through the first mentioned end in a manner as indicated in Fig. 1. The inner end of the element 14 is secured to the spherical member 12 by a fastening element 16, which may comprise a metal staple. 30

It is intended that the spherical member 12 and the associated member 14 may be manufactured separate from the balloon. It may be engaged in the balloon by first rolling up the neck portion of the balloon as indicated by reference 40 numeral 11' in Fig. 4. Then the spherical member 12 is placed on the rolled up neck portion 11' and the neck portion is now unrolled over the spherical member. Then by pressing on the spherical member through the neck portion of 45 the balloon, it is possible to force the spherical member into the main body of the balloon.

The operation of the device is as follows:

Normally the spherical member 12 freely depends within the main portion of the balloon 10. 50 The neck portion of the balloon may be engaged in one's mouth and the balloon inflated. The neck portion may be held closed with one's fingers. Thus the strand 14 may be pulled, and the neck portion released, so that the spherical member 14 quickly moves into a position in the base of the neck portion of the balloon as illustrated in Figs. 1 and 3. Now the spherical member 55 acts as a stopper holding the air within the 60

balloon. The strand 14 may be used as a handle for carrying the balloon around.

If the spherical member 12 is of cork or other material which may allow the escape of air slowly from the neck portion 11, in due time the balloon 14 will be deflated. It may be reinflated by first forcing the spherical member 12 down into the balloon, and then blowing through the neck portion as previously explained.

10 In Figs. 5 and 6, a modified form of the invention has been disclosed which distinguishes from the prior form in the construction of the spherical member and its operating element. In this form of the invention the spherical member 12 is formed with an incision 18 extended in from one side. Within this incision there is a means for expanding the compass of the spherical member to the sides of the incision. This means comprises a pair of arms 19 and 20 which are 15 pivotally connected together at one of their ends by a pintle 21. The outer ends of these arms are pivotally supported by pintles 22 and 23, respectively, within cavities 24 formed in the side walls of the incision 18. Small metallic or other rigid 20 strips of material 25 are set into the cavities 24 to limit outward pivoting of the arms 19 and 20. A rod 14' is pivotally mounted upon the 25 pintle 21, and at its outer end is provided with a ring portion 15'.

30 The air stopper and holder may be engaged into and out of a balloon in the same way as the preferred form. However after the toy balloon has been inflated the rod 14' is pulled to engage the spherical member 12' into the neck portion 11 of the toy balloon. Simultaneously when the rod 14' is pulled the arms 19 and 20 will be pivoted outwards, to the positions indicated in Fig. 6, where they engage against rigid elements 25. In these positions the arms 19 and 20 spread the material of the spherical member 12' to the sides 35 of the incision 18 increasing the compass of the spherical member at this area. This increased size of the spherical member will assist in plugging the neck of the balloon.

40 While I have illustrated and described the preferred embodiments of my invention, it is to be understood that I do not limit myself to the precise constructions herein disclosed and the right is reserved to all changes and modifications 45 coming within the scope of the invention as defined in the appended claims.

Having thus described my invention, what I claim as new, and desire to secure by United States Letters Patent is:

45 1. In combination with a toy balloon having a neck portion which may be inflated, a spherical member within said balloon and adapted to be plugged in said neck portion and having an incision in one side, means within said incision and movable to spread the compass of said spherical member, and an element connected with said means and extending from said neck by which the spherical member may be moved into plugging position.

50 2. In combination with a toy balloon having a neck portion which may be inflated, a spherical member within said balloon and adapted to be plugged in said neck portion and having an incision in one side, means within said incision and movable to spread the compass of said spherical member, and an element connected with said means and extending from said neck by which the spherical member may be moved into plug-

ging position, said means comprising a pair of arms pivotally connected at one of their ends, and at their outer ends pivotally connected at points upon the side wall of said incision, said arms normally being directed inwards, and means for limiting outward pivoting of the arms into a position in which the material of said spherical member is spread.

55 3. In combination with a toy balloon having a neck portion which may be inflated, a spherical member within said balloon and adapted to be plugged in said neck portion and having an incision in one side, means within said incision and movable to spread the compass of said spherical member, and an element connected with said means and extending from said neck by which the spherical member may be moved into plugging position, said means comprising a pair of arms pivotally connected at one of their ends, and at their outer ends pivotally connected at 20 point upon the side wall of said incision, said arms normally being directed inwards, and means for limiting outward pivoting of the arms into a position in which the material of said spherical member is spread, said element comprising a rod 25 which is pivotally connected with the pivotal connected ends of said arms.

4. In a device of the class described, a plug for closing a neck opening, comprising a spherical member adapted to be drawn into said neck opening and having an incision extending inwards from one side thereof, a pair of arms arranged in end alignment and located within said incision and having their outer ends pivotally connected to opposite walls of said incision and 35 their inner ends directed away from the open end of said incision and pivotally connected together, and a rod having its lower end pivotally attached to the pivot point of the inner ends of said arms and extending from the end of said neck opening, whereby said rod may be pulled for moving said spherical member into position in said neck opening after which said rod may be moved relative to said spherical member to pivot said arms past a dead center and until they are directed 40 towards the open end of said incision to expand said spherical member against the walls of said neck opening.

45 5. In a device of the class described, a plug for closing a neck opening, comprising a spherical member adapted to be drawn into said neck opening and having an incision extending inwards from one side thereof, a pair of arms arranged in end alignment and located within said incision and having their outer ends pivotally connected to opposite walls of said incision and their 50 inner ends directed away from the open end of said incision and pivotally connected together, and a rod having its lower end pivotally attached to the pivot point of the inner ends of said arms and extending from the end of said neck opening, whereby said rod may be pulled for moving said spherical member into position in said neck opening after which said rod may be moved relative to said spherical member to pivot said arms 55 past a dead center and until they are directed towards the open end of said incision to expand said spherical member against the walls of said neck opening, and small metallic strips mounted on the top wall of said incision to limit outward 60 pivoting of said arms to a position in which said spherical member will be expanded.

65 GEORGE MAGRAN.
